UNITED STATES PATENT OFFICE.

EDWARD BRUSH FINCH, OF NEW YORK, N. Y.

TOP FOR STOVES.

SPECIFICATION forming part of Letters Patent No. 286,536, dated October 9, 1883.

Application filed August 7, 1883. (No model.)

To all whom it may concern:

Be it known that I, EDWARD BRUSH FINCH, a citizen of the United States, residing at or in the city, county, and State of New York, have 5 invented a new and useful Improvement in the Tops for Stoves, of which the following is a specification.

My invention relates to the pieces used to vary the number and location of the holes in 10 stove-tops; and the object of my invention is to provide a stove-top that may be arranged to have either two or three holes at will, and in which, when arranged as a three-holed top, all three holes are nearly equidistant from the 15 center of the heat-current, while when arranged as a two-holed top one hole receives the heat direct; thence the heat-current passes direct to the second hole before finding egress from the stove; also, to provide a secondary 20 oil-stove stop in which the usual supporting-pieces may be entirely removed, enabling cooking or heating operations to be accomplished upon the primary top without disturbing or removing the secondary top. I attain these 25 objects by the construction substantially illustrated in the accompanying drawings of my improved top as applied to an oil-stove, in which—

Figure 1 is a top view of my improved top 30 arranged to have three holes. Fig. 2 is a top view of my improved top arranged to have two holes. Fig. 3 is a top view of my improved top with the pieces for supporting the cooking-utensils removed. Fig. 4 is a top view 35 of the piece designed to give to the stove-top three holes, and Fig. 5 is a top view of the piece for giving the top two holes.

Similar letters refer to like parts throughout the several views.

40 The secondary top T is provided with the two pieces A and B, either of which will fit into a suitable seat provided in the top in the usual manner. When the piece A is in position, as in Fig. 2, the secondary top is provided with two holes, one of which, F, is directly over the flame or heat openings C, and is therefore in the most effective position for 45 heating purposes, while the remaining heat passes direct to the second hole, G. When B

is in position on the stove-top, as shown in 50 Fig. 1, then the three holes D E G receive comparatively equal quantities of heat ascending through the flame-opening C. When both pieces A and B are removed, the primary 55 stove-top X, upon which my improved top is placed, may be utilized for all the purposes possible if my improved top was not on it, thus avoiding the necessity of removing my improved top, which is necessary in all other tops.

60 I am aware that prior to my invention means have been devised whereby to convert two holes into one by removing the center piece between the two holes and the use of two crescent-shaped pieces at the extremity of the 65 oval hole thus formed; but in such devices it has been impossible to accomplish this result without providing the top with either two removable pieces and a fixed plate, or else providing it with more than two removable pieces. 70 Furthermore, it has, in such prior devices, been impossible to place a vessel or utensil as large or larger than the primary top directly over the flame or heat openings and set it upon the usual supporting-pins, P, of the primary top 75 without removing or disturbing the top.

Having thus described my invention, what I claim as new, and desire to secure by Letters Patent, is—

80 The combination of the two movable pieces A and B with a stove-top of such shape that by using one or the other of such pieces the top can be used either as a three-holed top, with the holes nearly equidistant from the central heating-point of the stove, or as a two- 85 holed top with one of the holes directly over the fire and the other so located that all the heat passes directly beneath it, while by the non-use of the removable pieces A and B an oil-stove is made available as though no secondary top were used, thus avoiding the necessity of removing such secondary top, substantially as set forth.

EDWARD BRUSH FINCH.
